MACHINE FOR MAKING CELLULOSE SHEETS
AND THE LIKE

Emil Czapek, New York, N. Y.

Application August 3, 1940, Serial No. 350,289

10 Claims. (Cl. 18—15)

This invention relates to machines or devices for producing improved cellulose sheets, films or the like. The application is a continuation in part of my co-pending application Serial No. 158,746, filed August 12, 1937 issued as patent No. 2,234,964 on March 18, 1941.

Among the objects of the present invention, it is aimed to provide an improved machine for producing an improved cellulose sheet, film or the like of an exceedingly uniform physical structure throughout having a practically equal tension and shrinkage characteristic in length as well as in width.

It is still another object of the present invention to provide an improved machine for producing an improved cellulose sheet, film or the like of an exceedingly light thickness without striations and the like and having a width of forty inches or more by means of a continuously operating process.

It is still another object of the present invention to provide an improved machine for producing an improved cellulose sheet, film or the like of unusual thickness with an exceedingly uniform physical structure throughout.

These and other features, capabilities and advantages of the present invention will appear from the subjoined detail description thereof illustrated in the accompanying drawings, in which

Figure 1 is a side elevation more or less diagrammatically of one embodiment;

Fig. 2 is a side elevation of the feeding device used in the embodiment of Fig. 1;

Fig. 3 is a fragmental transverse section of the feeding device shown in Fig. 2;

Fig. 4 is a side elevation more or less diagrammatically of another embodiment;

Fig. 5 is a fragmental plan of the embodiment shown in Fig. 4;

Fig. 6 is a front elevation of one of the conveyor supporting idlers used in the embodiment of Fig. 4; and

Fig. 7 is a sectional view on line 7—7 of Fig. 3.

The present invention essentially uses a pouring base onto which a viscous cellulose solution such as a cuprammonium cellulose solution is poured evenly by means of an exact fitting nozzle or feeder. Thereupon, the solution which adheres to the base and cannot be subjected to stretching or extending, passes by moving or rotating at the base into a coagulation bath. In the coagulation bath which is in continuous movement, the poured sheet will be coagulated to a strip and only then removed when the coagu-

lation has been completed and the coagulation bath has penetrated the sheet to the pouring base. The film after removal has practically the same length and width as the formerly spread solution and furthermore does not change these dimensions in the following bath.

In the embodiment shown in Fig. 1, there is provided a feeder or nozzle for feeding or spreading a viscous cellulose solution directly onto a supporting base to enable the solution effectively to attach or adhere to the supporting surface and thereupon effectively spreading the solution into a thin layer. In the present instance, the supporting base is the face 2 of the drum 3, which, however, also may consist of an endless band or belt.

The drum 3 is rotatably mounted on the shaft 4 extending through the trough 5; the arcuate wall 6 of which is spaced from the face 2 a uniform distance throughout, while the end faces of the drum 3 are preferably closed and in engagement with the plane end baffles 7 of the trough 5. The drum 3 is preferably provided with a metal cylindrical wall member to provide the supporting face 2, the wall being composed as an instance of either iron, steel, nickel or the like, or the wall provided with a coating of nickel, chromium or the like and then either highly polished to form a glossy or glistening surface, or else dull finished or a graduation of one or the other according to the surface finish of the film, sheet or the like to be produced.

The cellulose solution is introduced by the hopper or nozzle 1 to the surface 2 of the drum 3, the hopper 1 having a long narrow feeder discharge 8, the opening of which is adjustable by the pivotally mounted wall member 9.

When enlarging or narrowing the discharge opening by shifting the wall part 9, accordingly more or less cellulose solution will flow through the opening 8 onto the pouring base 2. The hopper itself is supported in a bracket or in two levers 12 which are pivotally connected to rotate about the two pivots 13 on the frame constituting a part of the wall 6 and are provided with two rollers 14 resting on the edges of the drum 3. The hopper is adjustably mounted in the bracket 12 and rests on the pouring base by means of two rotating rollers 146. The position of the hopper is regulated through screw 11.

In order to prevent any vagrant discharges from the sides of the feeder 1 for the several adjustments possible, there are provided the vertically adjustable end plates or baffles 147 having

vertically extending slots 143 cooperating with the wing nuts 149.

Attached to the lower edge of the wall 10 of the nozzle is a blade or bar 15 which has been tapered into a knife-like edge and by a set of screws 16 and 160 the position thereof may be adjusted. The adjustment must be to the finest extent and very exact, as the thickness of the film is adjusted and regulated hereby.

The thickness of the finished film is determined by the amount of cellulose solution 20, which the knife-like lower edge of the blade 15 leaves on the pouring base 2.

The width of the slot 8 of the feeder will be adjusted through changing the position of wall 9 to insure supplying onto the base 2 sufficient cellulose solution in advance of the edge of the blade 15, so that the cellulose solution will be sufficiently and effectively spread out on the pouring base 2 below the feeder. The position of wall 9 is adjusted by actuating the eccentric 190. The width of the opening of the feeder 1 depends upon the thickness of the film to be manufactured, on the velocity of the drum 3, and on the viscosity of the cellulose solution.

The drum rotates in the direction of the arrow 116. The cellulose solution is spread directly on the dry surface by rotating the drum 3, without passing through a free intermediate space and thereupon passes into trough 5 and is here coagulated by the fluid contained therein. The position of the hopper 1 is such that the blade 15 in advance of the slot 8 is disposed below the upper level of the drum 2 and on the side of the drum 2 with reference to the arrow 116 so that it will cooperate or is operatively associated with a downwardly moving portion of the surface of the drum 2 relative to the upper level of the drum 2 to enable accumulating the supply medium on the drum and to prewet the surface of the drum 2 before the surface so wetted comes beneath the lower edge of the blade 15.

The trough 5 will be supplied with a treating fluid introduced through the inlet 17 with a treating fluid consisting essentially of sodium hydroxide, ammonia and copper, which is discharged through the outlet 18.

It will be noted that the inlet 17 and the outlet 18 are disposed at the upper level of the fluid in the trough 5 and at the opposite ends thereof, the inlet 17 just below the position where the film 19 leaves the drum 3 and the outlet 18 a short distance below where the solution 20 is initially poured on the outer face 2 of the drum 3.

The concentration and the velocity of the fluid flowing through trough 5 is determined by the components of the influential solutions and fluids, hereinafter set forth in detail.

The film layer 19 will adhere to the surface 2 of the drum 3 during the entire coagulation process and does not permit that any part of the fluid in trough 5 penetrates between the face 2 and the adhering surface of the layer 19. Only after the coagulation has been completed, will the coagulation fluid penetrate through the coagulated layer 19 and thereby arrive at the surface 2 of the drum 3 which it now wets. Furthermore, only after this has been accomplished will the sheet 19 be taken from the drum 3.

For a proper coagulation of layer 19, it is important that the coagulation fluid in trough 5 flows past layer 19. In order to effect a good flow or movement of the fluid, trough 5 is so shaped that only a small space intervenes between the pouring face 2 and the opposite wall of

the trough 5 in the entire extent through which the coagulation fluid flows. Velocities of two inches per second and above for the movement of the fluid are preferred.

8 The thus produced sheet or strip 19 may be removed from the surface 2 without difficulty. It is completely coagulated and still of the same length and width as at the beginning of the process. The strip 19 passes now for a short time 10 through another trough containing a coagulation fluid in order to wet that surface of the sheet which had not been touched by the coagulation bath so long as it remained on the base 2.

15 After the layer 19 leaves the bath in the trough 5 and while still in adhesive engagement with the face 2 of the drum 3 until the face 2 entirely clears the upper level of the bath, the layer 19 then passes onto the outer surface of the roller 21 from which it passes into the container 20 22 so that the face of the layer heretofore in engagement with the face 2 of the drum 3 may now be effectively covered with a coagulation fluid similar to that contained in the trough 5.

25 In order effectively to dry the surface 2 and thereby remove any deposits, moisture and the like either from the strip 19 or from the trough 5 after the strip passes onto the roller 21 and in the area of the surface 2 disposed between the roller 21 and the nozzle 1, there are provided 30 scraping means, such as the scrapers 142 and 143 consisting in the present instance of the blades pivotally mounted on the shaft 144 and 145 so that as here shown they rest by gravity on the surface 2 and in opposition to the direction of movement of such surface 2.

35 After leaving the roller 21 and in order to facilitate guiding the strip 19 through the bath 23 in the container 22, the strip next passes down under the roller 24 near the lower end of the container 22, then up above the roller 25 40 before being passed into the water 28 in the next container 29 where any of the bath fluid adhering to the outer faces of the strip 19 is now effectively washed off and some of the coagulation bath fluid which has generated the strip or been diffused into the same will be diluted and removed in part. For convenience, the strip 19 after leaving the roller 21 first passes around 45 the roller 30 adjacent the lower end of the tank 29, then around the upper roller 31, again down around the lower roller 32, again up and around the upper roller 33, again down and around the roller 34 and then up out of the tank 29 around 50 the roller 35 before being introduced into the acid bath 36 contained in the tank 37.

55 The strip 19 will be guided into and out of the acid bath 36 by means of the rollers 38 to 43 inclusive, in the manner well known in the art, 60 where the strip 19 will be regenerated and the copper effectively removed.

65 After the strip 19 has been completely freed of the copper, it is now passed through several baths of clean, clear water and impregnated with softeners or plasticizers and dried. For drying the strip 19, the same is passed either through a well-known drying cylinder, not shown, or subjected to a stream of warm air supplied by a suitable blower or the strip subjected to a combination of both such drying treatments.

70 Preferably, in the embodiment just described, as shown in Fig. 1, the inlet 44 is connected to an extended tubular spray 150 having a plurality of branches extending adjacent to the path of 75 movement of the strip 19 and provided with dis-

charge openings directed at the face of the strip 19.

In the embodiment illustrated in Fig. 4, instead of permitting the strip here designated 119 to extend freely from one roller to the other, while passing through the secondary coagulation bath 123 in the tank 122 and while passing through the water 128 in the tank 129, it will be supported on the endless band 46 with the surface of the strip 119 exposed which formerly adhered to the face 102 of the drum 103. When so supported on the endless band 46, it will be noted that the rollers 140 in the lower portion of the tank 122 will be chambered at 141 so that the exposure of the face of the strip 119 here sought will not be interrupted.

Furthermore, in this embodiment, instead of permitting strip 119 to extend freely from one roller to the other while passing through the acid bath 136 in the tank 137, it will here pass directly from one roller to another, see the upper row of rollers 47 and the lower row of rollers 48 staggered relative to one another and overlapping one another effectively to support the strip 119 throughout its passage through the tank 137. Here, too, the acid bath is constantly being renewed and being fed to the several inlet pipes 49 with discharge openings directed at the faces of the strip 119, as they pass from one roller to the other. The tank 137 is also provided with an outlet 50 to permit the bath fluid to pass therefrom so that the copper, if in excess of five per cent, may be removed therefrom and fresh acid supplied to the predetermined concentration.

It is of course obvious that the baths 23 and 28 as well as the baths 123 and 128 may be renewed continuously as well as the other baths.

While it is desired not to be limited to the proportions, hereinafter set forth, it is claimed that the proportions here used in the process disclosed and machines used are new and particularly advantageous.

As an instance, excellent results have been achieved when the steps now to be described and proportions indicated are selected.

First, it is well to note that it is desirable to observe the chemical proportions hereinafter set forth so that the coagulation may take place correctly and tension-free into the inside of the solution in order to facilitate faultlessly removing the finished strip 19 from the base 2 when the strip has already so solidified that there will be no disadvantageous changes by the ensuing treatments in tanks 22, 29, 31 and the like.

The solution 20 introduced through the nozzle 1 consists essentially of an amount of cellulose corresponding to 5 to 8 per cent by weight of the entire solution, an amount of ammonia corresponding to 45 to 85 per cent by weight of the cellulose content, an amount of copper corresponding to 36 to 43 per cent by weight of the cellulose content, and an amount of sodium hydroxide which should not exceed 44 per cent concentration of the cellulose.

The fluid in the trough 5 constituting the coagulation bath, should consist essentially of a watery solution of sodium hydroxide in proportion of 5 to 9.5 per cent by weight of the bath, of ammonia in proportion of 0.1 to 0.5 per cent by weight of the bath, and of copper, dissolved in the fluid, of 0.1 to 1.2 per cent by weight of the bath.

The easiest manner of adding the agents supplementary to the sodium hydroxide is by starting the process with a coagulation bath of sodium hy-

dioxide in the proportions heretofore recited and dissolving the other agents by the coagulation of a smaller amount of the cellulose. The coagulation bath absorbs the ammonia and the copper of the cellulose solution at once and the concentration of the proportions in this way will be quickly standardized which has to be observed during the process.

The transformation of the cellulose solution 10 20 into a solid strip is done by dipping the pouring base 2 covered with the layer 19 by rotating or other movement of the base 2 into the coagulation bath in trough 5. The cellulose layer 19 is here coagulated from one side while the other side 15 adheres closely and unmovably to the base 2 until the coagulation is completed.

The effect or rather the changes which take place in the layer 19 while passing through the trough 5 with the recited proportions of the ingredients both in the solution and in the fluid 20 constitute the important steps in the process for obtaining uniform and tension-free strips. It has been found essential and advantageous that the ammonia which during the coagulation diffuses 25 from the cellulose layer 19 into the coagulation fluid in the trough 5 is immediately washed out. Therefore, it is better that the coagulation fluid passes in a stream along the solution layer 19 throughout its entire extent and in an opposite direction to the movement of the pouring base 2. Only by maintaining the coagulation bath in motion in this way can the ammonia content be watched so that a detrimental accumulation on the boundary surface will be avoided.

The rate of flow of the fluid through the trough 35 5 will be determined by the respective components or ingredients of the solution introduced through the nozzle 1, the ingredients of the fluid in trough 5, the velocity of the movement of the base 2, the 40 thickness of the layer 19, and finally the extent and width of the fluid passage formed by the trough 5 and the base 2. Therefore, when the velocity of the flow is proper, it will be possible to maintain the total concentration of the ammonia 45 in the coagulation fluid below 0.8 per cent by weight, and the risk of a detrimental accumulation of ammonia on the boundary surface or in pockets will be avoided.

Since during the process by continuous coagulation 50 additional quantities of ammonia will steadily enter into the coagulation bath from the cellulose layer, the ammonia has to be continuously removed from the coagulation bath so that the concentration of ammonia will not exceed 0.8 per cent by weight. This is accomplished as an 55 instance when the fluid is removed from trough 5 through the discharge 18, the ammonia thereupon distilled off so that it will again be reduced to 0.1 to 0.5 per cent by weight of the fluid and this fluid then cooled off and returned to the 60 trough 5 through the inlet 17.

The accumulation of copper in the fluid content of the trough 5 can ordinarily be ignored if care is exercised occasionally to remove the copper 65 content when it exceeds 0.1 to 1.2 per cent by weight of the fluid.

The next step will be the washing of the strip 19 in order to rinse off the adhering part of the coagulation fluid as well as to dilute and partly 70 remove the coagulation fluid seeped into the strip 19.

The rinsing or soaking of the strip 19 after it has been removed from the base 2, eventually, as set forth passes a second coagulation bath 75 when it will be subjected to a bath of either water

or a weak solution of sodium hydroxide. The rinsing may only be continued until the constituents of the strip 19 have been reduced to 20 parts by weight of copper, 3 parts by weight of ammonia, and 22 parts by weight of sodium hydroxide, referring to a 100 parts by weight of cellulose. If the rinsing process should continue after this reduction has been reached, the strip 19 is in danger of becoming too delicate and deformed resulting in destructive internal tensions, irregularities, striations and the like.

The washed film thereupon is passed into an acid bath in which the cellulose will be entirely regenerated and the copper will be removed from the strip. It has been found advantageous to use a sulphuric acid bath of more than 2 and less than 5 per cent by weight at temperatures of more than 75 and less than 125 degrees Fahrenheit.

In this bath the shrinking of the strip takes place initially. Hereby a satisfactory uniform treatment of the strip 19 without inducing any tensions, shrinkages or the like in the same can be obtained, if the preliminary coagulation and washing has been done in a careful manner, and the concentration, temperatures and the like have been followed closely, as mentioned.

Preferably also the bath 36 is being continually renewed, the bath fluid entering the tank 37 through the inlet 44 and leaving the tank 37 through the outlet 45 so that the bath fluid flows past the strip 19. In order to have the acid solution spread uniformly onto the strip, the inlet 44 is connected to an extended tubular spray 44 and branchways. The copper dissolved in the acid solution will be removed from the fluid which is discharged through outlet 45, and the fluid will again be replenished with fresh acid and reheated to the desired temperature. The copper content of the acid solution should not exceed 5 per cent by weight of the bath fluid.

After the strip 19 has been completely freed of copper, it is now passed through several baths of clean, clear water and impregnated with softeners and plasticizers and dried.

Strips made according to the present process and by the present machine are characterized by not having been stretched, extended or shrunk to any appreciable extent during the process of coagulation and washing resulting in a uniform physical structure throughout, free from striations, streaks and irregularities of any kind.

On account of the uniform treatment on the base in the first stage of the process when the transformation from the liquid into the solidified state takes place, the process is especially suited for the manufacture of thin strips and has been developed especially for this purpose.

In accordance with present process, it is possible to manufacture strips not only having a weight of less than 0.35 ounce per thousand square inches, but also having a weight of less than 0.20 ounce and less than 0.10 ounce per thousand square inches, all characterized by being without striations, streaks and irregularities of any kind.

However, this process is also suited for the manufacture of unusually thick films. As the coagulation of thick layers develops very slowly, it is necessary to retard the velocity of the drum 3 so that the coagulation may be finished on the base. Since, however, the coagulation in this process always takes place on the base, it is uniform and without tensions and stretchings. Therefore, this process is also particularly adapted

to produce films of six ounces per thousand square inches.

The words "directly spreading," "spreading directly," "spreading out," and the like, wherever used in the specification and claims are intended to cover the forming of the cellulose solution into a thin layer on the dry supporting surface in the manner of smearing or brushing the same after a sufficient supply has been received by and supported onto said surface without any free air space between the nozzle, layer and dry supporting surface. In other words, the thickness of the layer being spread out effectively fills up the space between the nozzle, spreading blade 15 and the supporting surface 2.

It is obvious that various changes and modifications may be made to the details of construction without departing from the general spirit of the invention as set forth in the appended claims.

What I claim is:

1. The combination with a movable support of a pouring device adapted for the production of thin films having a thickness uniform in the length and in the width by pouring a cellulose solution on said support including a hopper for containing a cellulosic solution adjustably disposed on the edges of said support and having an elongated feeder at its lower end, the feeder having a discharge opening operatively associated with said support, a blade extending the entire width of the feeder and adjustably connected to said feeder, and end baffles adjustably connected to the sides of the hopper for engaging the surface of said support and extending parallel to the path of movement of said support.
2. The combination with a movable support of a pouring device adapted for the production of thin films having a thickness uniform in the length and in the width by pouring a cellulose solution on said support including a hopper for containing a cellulosic solution, two pivotally mounted levers having their free ends engaging said support, said hopper being adjustably suspended by said levers and having an elongated feeder at its lower end, the feeder having a discharge opening adjustable for controlling the escape of the cellulose solution, a blade extending the entire width of the feeder and adjustably connected to said feeder, and end baffles disposed at the outer sides of the hopper, extending parallel to the path of movement of said support, and adjustably connected for engaging the surface of said support independently of the predetermined position of the feeder and the blade.
3. The combination with a movable support of a pouring device adapted for the production of extremely thin films having a thickness uniform in the length and in the width by pouring a cellulose solution on said support, including a hopper for containing a cellulosic solution adjustably disposed on the edges of said support and having an elongated feeder at its lower end, the feeder having a discharge opening operatively associated with said support, means to regulate the opening of the feeder discharge to control the escape of supply medium, a blade at the advance side of the feeder discharge, means adjustably connecting said blade to said feeder for precisely regulating with uniformity the distance between the lower edge of the blade and the surface of said support throughout the length of the blade, end baffles adjustable on the outer sides of the hopper and extending parallel to the path of movement of said support, and means to regulate

the position of said baffles to engage the surface of said support, independently of the predetermined position of the feeder and the blade.

4. The combination with a movable support of a pouring device adapted for the production of extremely thin films having a thickness uniform in the length and in the width by pouring a cellulose solution on said support, including a hopper for containing a cellulosic solution adjustably disposed on the edges of said support and having an elongated feeder at its lower end and a movable back wall, the feeder having a discharge opening operatively associated with said support, means to regulate the opening of the feeder discharge to control the escape of supply medium by moving said back wall, a blade extending the entire width of the feeder, means adjustably connecting said blade to said feeder at several points for precisely regulating with uniformity the distance between the lower edge of the blade and the surface of said support throughout the length of the blade, and end baffles adjusted on the outer sides of the hopper and extending parallel to the path of movement of said support, to effect the closure of the space laterally between the feeder discharge, the blade and the surface of the support immediately adjacent to the discharge and the blade.

5. The combination of a coagulation bath, a drum rotatably mounted in said bath with a segment of said drum exposed, a device mounted above said exposed segment and adapted to deposit a viscous film forming solution upon the surface of said drum, said device including a hopper having an elongated feeder and a regulatable outlet at its lower end, and having two supporting rollers engaging the surface of the drum, a blade adjustably connected with the feeder at several points on the advance side of the feeder and operatively associated with the surface of the drum for spreading the deposited solution evenly in a thin film layer, the discharge edge of the blade being in substantial alignment with the contact points between said rollers and drum, means for precisely regulating with uniformity the distance between the lower edge of the blade and the surface of the drum independently of the position of the hopper, and end baffles adjustably connected to the feeder at its sides to prevent any vagrant discharge from the sides of the feeder.

6. The combination of a frame, a coagulating bath, a drum rotatably mounted in said bath with a segment of said drum exposed, levers pivotally connected to said frame having rollers at their free ends engaging the surface of said drum, a hopper mounted above the exposed portion of said drum, adjusting means for adjustably suspending said hopper between, and anchoring said hopper to, said levers, said hopper including a feeder at its lower end and the feeder having a discharge opening operatively associated with a downwardly moving portion of the drum surface to accumulate the supply medium on and pre-wet the drum surface before said surface comes beneath the feeder discharge opening, and a sharp edge blade adjustably connected to the advance side of the feeder at several points to spread out the supply medium accumulated on the drum surface evenly to a uniform film layer.

7. The combination of a coagulating bath, a drum rotatably mounted in said bath with a segment of said drum exposed, a hopper includ-

ing a feeder at its lower end, mounted above and spaced from the exposed segment of said drum, said hopper having a movable back wall and the feeder having a discharge opening operatively associated with a downwardly moving portion of the drum surface permitting the supply medium after passing the discharge opening to accumulate on and pre-wet the drum surface before said surface comes beneath the feeder discharge opening, a tapered blade at the advance side of the feeder discharge opening and means adjustably connecting said blade to said feeder at several points to facilitate precisely regulating with uniformity the distance between the lower diminished edge of the blade and the surface of said drum throughout the length of the blade to spread out the supply medium accumulated on the drum surface to a thin film layer.

8. The combination of a coagulating bath, a drum rotatably mounted in said bath with a segment of the drum exposed, a feeder having a discharge opening operatively associated with said drum, means for adjustably mounting said feeder to position the discharge opening above the downwardly moving portion of the drum surface, a blade adjustably connected to the lower end of the feeder at the advance side of the feeder, means for precisely regulating with uniformity the distance between the lower edge of the blade and the surface of said drum portion, end baffles connected to the sides of the feeder and extending parallel to the path of movement of the drum surface, and means for adjustably connecting said end baffles to position said end baffles in effective engagement with said drum surface independently of the predetermined position of the feeder and the blade to effect the closure laterally of the space between the feeder discharge opening, blade and drum surface.

9. The combination of a movable supporting base, a feeder adjustably disposed on the lateral edges of said supporting base and having its discharge end disposed at the base, a blade adjustably connected with the feeder on the advance side of the feeder discharge opening, end baffles adjustably connected to the sides of the feeder effectively to engage the surface of the face throughout their widths and bounding both ends of the blade and of the lower end of the feeder discharge opening, all to enable supplying a cuprammonium cellulose solution directly onto said supporting base and to enable spreading such solution, so accumulated between the discharge opening, the blade, the baffles and the supporting base, into a thin layer on the base, a coagulation bath for carrying out the coagulation of the cellulose solution, the received layer being supported by said movable base during the coagulation treatment in said bath, and means for detaching the coagulated cellulose structure from the supporting base after the cellulose structure passes out of the coagulating bath.

10. The combination of a metallic cylindrical rotatable supporting base having a highly polished surface finish, a feeder adjustably disposed on the lateral edges of said supporting base and having its discharge opening end disposed at the base, a blade adjustably connected with the feeder on the advance side of the feeder discharge, end baffles adjustably connected to the sides of the feeder effectively to engage the surface of the base throughout their widths and

bounding both ends of the blade and of the lower end of the feeder discharge opening, all to enable supplying a cuprammonium cellulose solution directly onto said supporting base and to enable spreading such solution, so accumulated between the discharge opening, the blade, the baffles and the supporting base, into a thin layer on the base, a coagulation bath for carrying out the

coagulation of the cellulose solution, the received layer being supported by said movable base during the coagulation treatment in said bath, and means for detaching the coagulated cellulose structure from the supporting base after the cellulose structure leaves the coagulating bath.

EMIL CZAPEK.
